Claims priority, application Germany Apr. 19, 1958
8 Claims. (Cl. 192—84)

Our invention relates to an electromagnetic clutch of the stationary magnet type in which there is an axially directed air gap between the stationary magnet portion and the movable magnet portion having equal areas on either side of the air gap, and utilizes radiating fins on the stationary magnet portion for cooling purposes.

In the prior types of stationary magnet clutches, the magnetic structure includes a stationary portion and a movable portion which are magnetically connected through a first and second air gap. These air gaps have previously been at least partially radially directed whereby an axial force is imposed upon the movable magnetic portion, thus necessitating radial bearing means.

In our invention, this problem is overcome through the use of axially directed air gaps instead of radially directed air gaps between the stationary magnet portion and the movable magnet portion.

In the axially directed air gap the gap on the larger diameter will have a larger cross-sectional area if the axial length of the air gap faces are the same. We have recognized this problem, and have overcome it by providing a U-shaped stationary magnet structure which contains a trapezoidally shaped energizing coil, and a co-operating trapezoidally shaped protrusion from the movable magnet structure extends into this opening. The two legs of the U-shaped stationary magnet thus meet the protruding portion of the movable magnet structure along axially directed air gaps. Since, however, the protruding portion of the movable structure is trapezoidal in shape, the outer air gap will have a small axial length than will the inner air gap whereby the total cross-sectional area of the two air gaps may be made identical so that the radial forces on the movable magnetic structure are exactly balanced.

We have further found that the torque capacity of the clutch has been limited because of heat generated within the energizing coil of the magnet body, and thus places a limit on the amount of heat that may be generated by the engaging clutch laminations. To increase the heat due to the energizing coil, and thus permit an increase in the heat generated by the laminations, we have found that the stationary magnet structure can be formed with a heat transfer means, such as radially directed fins which will both increase the external area of the stationary magnet structure and so increase its heat transfer ability, as well as permitting additional cross-sectional area for the passage of magnetic flux.

As a second embodiment, we have found that a funnel means can be attached to the stationary magnet structure for clutches of the type which operate in an oil mist atmosphere whereby oil is condensed and collected in the funnels. These funnels may then communicate with apertures which lead to the internal diameter of the clutch laminations whereby centrifugal force will drive the oil so conducted into the lamination area. Thus, the oil so collected will pass through the stationary magnet to effect some cooling thereof, and thereafter will reach the lamination area to continue to exert a cooling effect on the laminations.

Accordingly, a primary object of our invention is to provide a novel stationary magnet type of electromagnetic

2

clutch wherein the effect of the flux passing from the stationary magnet portion to a movable magnet portion exerts substantially no influence on the two parts.

Another object of our invention is to provide a novel electromagnetic clutch which yields high load capacities for minimum dimensions.

A further object of our invention is to provide a novel manner for cooling electromagnetic clutches of the stationary magnet type.

10 Yet another object of our invention is to provide a novel electromagnetic clutch wherein a stationary magnet is magnetically connected to a movable magnet portion through an axially directed air gap.

A still further object of this invention is to provide 15 axially directed air gaps for connecting a stationary magnetic structure to a trapezoidally shaped movable magnetic structure whereby the axial length of the outer air gap is less than the axial length of the inner air gap so that the total cross-sectional areas of the outer and 20 inner air gaps are substantially the same.

These and other objects of our invention will become apparent from the following description when taken in connection with the drawings, in which:

FIGURE 1 shows a first embodiment of our invention 25 wherein the movable magnetic structure of a stationary magnet clutch is trapezoidally shaped, and the stationary magnetic structure is provided with cooling fins.

FIGURE 2 is a side view of the clutch of FIGURE 1 when seen from the left-hand side, and particularly 30 illustrates the radially directed cooling fins.

FIGURE 3 is a second embodiment of our novel invention wherein the bushing carrying the inner laminations is externally positioned with respect to the inner portion of the rotatable magnet structure.

35 FIGURE 4 is a still further embodiment of our invention, as shown in FIGURE 1, wherein a cooling medium for the clutch is a funnel device associated with a cooling plate and oil bore holes.

FIGURE 5 is a side view of FIGURE 4 when seen 40 from the left-hand side.

FIGURE 6 is a cross-sectional view of FIGURE 4 when taken across the lines 6—6.

Referring now to the figures, we have illustrated our invention in connection with a generally well known type 45 of stationary magnet clutch wherein a shaft is selectively connected to an output device, such as a gear, through a stack of interleaved laminations. For details of clutches utilizing this general construction, reference is made to copending application Serial No. 811,428, filed 50 May 6, 1959 and assigned to the assignee of the present invention.

In the embodiment of FIGURE 1, a stationary magnet body 1 has a U-shaped cross-section which surrounds the magnet coil 2, and is supported with respect to shaft 3, which may be the driving or driven member, by the needle bearing structure 4. Needle bearing structure 4 is described in detail in the above noted application, Serial No. 811,428.

60 The outer left-hand portion of magnet body 1 is provided with a plurality of cooling ribs 5, as shown in FIGURE 2, which are of the same magnetic material as is body 1, and may be formed integrally therewith. The cooling ribs 5 serve the dual function of increasing the external area of magnet body 1 so that it may be more effectively cooled by a cooling medium, and they further serve to conduct magnetic flux through body 1.

The movable portion of the magnetic structure for generating flux through interleaved laminations of the clutch is generally shown as the trapezoidally shaped ring 6 which is magnetically connected to the stationary body 1 by the inner and outer axially directed air gaps

6a and **6b** respectively. This trapezoidal cross-section is permissible because of the trapezoidal shape of coil **2**, although it will be apparent to those skilled in the art that coil **2** may have the usual configuration of a rectangle, while the legs of the U-shaped magnet **1** may be of different lengths, so that when the movable magnet structure **6** encloses the opening of the stationary magnet it will, of necessity, have a trapezoidal shape.

Since the axially directed air gaps **6a** and **6b** which connect movable structure **6** and stationary structure **1** lie on different diameters, their total area would be different if the axial length of the gaps were the same. That is to say, the outer air gap which would have a greater diameter would have a greater total cross-sectional area than a smaller diameter air gap. However, by forming the movable magnetic portion **6** in a trapezoidal shape, we have made the axial length of the outer air gap smaller than the axial length of the inner air gap whereby the total cross-sectional area of the outer air gap is made the same as the total cross-sectional area of the inner air gap. In this way, it is apparent that a uniform magnetic flux is obtained, and there is no net axial force imposed on the movable magnetic structure **6**, since all of the air gaps are axially directed.

In order to prevent short circuiting of the magnetic flux by ring **6**, an intermediate annular insert **7** of non-magnetic material is provided therein which has a conical cross-section having its larger base surface facing the magnet coil and its smaller base section facing the lamination pack. More specifically, the clutch laminations of FIGURE 1 are shown as outer laminations **8** which cooperate with alternately positioned inner laminations **8a**. Each of the laminations is provided with a non-magnetic annular zone **9** which may be an air gap or a non-magnetic insert, as described in copending application Serial No. 811,428 filed May 6, 1959, and assigned to the assignee of the present invention.

The smaller base portion of non-magnetic member **7** is immediately adjacent the position of the non-magnetic zones **9**. The inner laminations of the lamination pack are supported by a cylindrical holder which is preferably of non-magnetic material in order to prevent leakage flux which by-passes the lamination pack.

In FIGURE 1, the inner disk holder, or support member **10**, has a sleeve **11** forced thereon which is of non-magnetic material. Sleeve **11** has a collar **12** integral therewith which is adjacent the face of the lower leg of magnet body **1** to prevent the axial passage of flux from the lower portion of magnet body **1**.

Sleeve **11** is directly connected to shaft **3** so that it is rotated by shaft **3**. Thus, the inner laminations **8a** connected to inner lamination support **10** will be rotated with shaft **3**.

The outer laminations, such as lamination **8**, are connected to an outer disk support **14** which may subsequently be connected to a driving or driven member, such as a gear. The inner disk support **10** is directly fastened to movable magnetic portion **6** by means of radially disposed screws, such as screw **15**.

In order to prevent leakage flux from the inner diameter of magnet body **1**, its supporting needle bearings are provided with a cage of non-magnetic material, such as brass, while the needle bearings, structure **4** of FIGURE 1, are shown as having an internal race which is directly connected to shaft **3**. This race may be eliminated with the bearings **4** riding directly on a hardened outer surface of shaft **3**.

Furthermore, the number of needle bearings in the cage may be reduced to as small a number as possible in order to keep the area for passage of flux as small as possible.

In operation, and assuming that shaft **3** is the driving member, as shaft **3** is rotated it will rotate lower disk support **10** and the inner laminations of the lamination pack and movable magnetic structure **6** which rotates

with respect to stationary magnet **1**. When coil **2** is energized it will generate a flux, as shown by the dotted lines in FIGURE 1, which circulates from the stationary magnetic body **1** through the axially directed air gaps to movable magnetic structure **6**, through the interleaved lamination pack to an armature **9a**, and thence back through the lamination pack magnet structure **6** and back to stationary magnet **1**. Since the armature **9a** and the interleaved inner disks **8a** are carried by the non-magnetic support **10** to be rotatable therewith, but axially movable therewith in the usual manner, the armature **9a** will move to the left to compress the stack of laminations against the right-hand surface of movable magnetic structure **6**. Thus, the inner laminations will be connected to the outer laminations through the frictional engagement of the interleaved disks, and outer disk support **14** will, in effect, be directly connected to shaft **3**.

In a second embodiment of our invention, as shown in FIGURE 3, movable magnetic structure **16** corresponds to movable magnetic structure **6** of FIGURE 1. The movable structure **16** is directly connected to shaft **3** by means of an extending collar or hub **17**, and further provides a plurality of extending fingers, such as finger **16a**, which serves as an outer disk support for the outer laminations of the lamination pack.

As was the case in FIGURE 1, the movable magnetic structure **16** has a trapezoidally shaped cross-sectional area so that the total cross-sectional area of the outer diameter axial air gap **18a** is the same as the cross-sectional area of the lower diameter axial air gap **18b**, and is provided with an insert **13** of non-magnetic material to prevent the short circuiting of flux by the movable magnetic structure **16**.

In the embodiment of FIGURE 3, the movable magnetic structure will simultaneously serve as a means for guiding the flux into the lamination pack as well as a means for transmitting mechanical force. An inner lamination support **19** which carries the inner laminations in the usual manner is an extending hub of an output drive member, such as a gear. Thus, when the lamination pack is compressed, the driven member connected to hub **19** will be directly connected to shaft **3** through the movable magnetic structure **16**. In order to prevent leakage flux, a plate **22** of non-magnetic material is positioned between the lower portion of the movable magnetic structure **16** and the lower portion of the stationary magnet **1**.

The operation of the structure of FIGURE 3 is similar to that described for FIGURE 1 where flux generated in stationary magnet **1** will first traverse the outer diameter air gap **18a** and then pass through the lamination stack to armature **9a**, and thereafter return through the lamination pack to the lower portion of the movable magnetic structure **16**, and thence through the inner axial air gap **18b** and back to the stationary magnet **1**.

FIGURES 4, 5 and 6 show a further embodiment of our novel invention in connection with a clutch of the general type shown in FIGURE 1. In FIGURES 4, 5 and 6, however, we have replaced the cooling ribs **5** of FIGURE 1 by a plate **26** which is directly fastened to the end surface of stationary magnet **1**. Cooling plate **26**, which is stationary, carries an upright funnel **27** which communicates with bores **28** and **29** in magnet body **1**. Bore **29** extends through the magnet body and terminates in openings **30** in ring **10**. Openings **30** then communicate with the lamination pack formed by the inner and outer laminations through the radial openings **32**, as best seen in FIGURES 4 and 6.

In operation, if the clutch is contained within an enclosed housing with an oil mist used for lubrication, it will be apparent that oil will condense on cooling plate **26** and flow downwardly into funnel **27**. From funnel **27** the condensed oil will pass through bores **28** and **29** and into openings **30** in the inner disk support **10**. Since the inner disk support **10** rotates, the oil will be forced outwardly and through radial bores **32** toward the clutch

disks. In this manner, the frictional heat produced from the clutch disks is transferred to the oil which is subsequently thrown out of the lamination pack. In the event that there is no oil mist for the operation, the funnel 27 may be supplied with oil through an adjacently positioned pipe, such as pipe 33.

Although we have described preferred embodiments of our novel invention, many variations and modifications will now be obvious to those skilled in the art, and we prefer therefore to be limited not by the specific disclosure herein but only by the appended claims.

We claim:

1. In an electromagnetic clutch; a stationary magnetic structure and a movable magnetic structure; said stationary magnetic structure having an annular opening therein; said annular opening receiving a coil at the bottom thereof; said movable magnetic structure including a ring shaped member; at least a portion of said ring shaped member being movably positioned within said annular opening of said stationary magnetic structure and being rotatable with respect to said stationary magnetic structure; said movable magnetic structure being magnetically connected to said stationary magnetic structure by air gaps along the inner and outer diameter of said annular shaped opening in said stationary magnetic structure; said portion of said ring shaped member positioned within said annular opening having a trapezoidal shape whereby the total area of said air gaps effective to transmit force to said movable magnetic structure on said inner and outer diameters of said annular opening are substantially equal.

2. In an electromagnetic clutch; a stationary magnetic structure and a movable magnetic structure; said stationary magnetic structure having an annular opening therein; said annular opening receiving a coil at the bottom thereof; said movable magnetic structure including a ring shaped member; at least a portion of said ring shaped member being movably positioned within said annular opening of said stationary magnetic structure and being rotatable with respect to said stationary magnetic structure; said movable magnetic structure being magnetically connected to said stationary magnetic structure by air gaps along the inner and outer diameter of said annular shaped opening in said stationary magnetic structure; said portion of said ring shaped member positioned within said annular opening having a trapezoidal shape whereby the total area of said air gaps on said inner and outer diameters of said annular opening are substantially equal; said coil having a trapezoidal shape cooperating with said trapezoidal shape of said portion of said ring shaped member.

3. In an electromagnetic clutch; a stationary magnetic structure and a movable magnetic structure; said stationary magnetic structure having an annular opening therein; said annular opening receiving a coil at the bottom thereof; said movable magnetic structure including a ring shaped member; at least a portion of said ring shaped member being movably positioned within said annular opening of said stationary magnetic structure and being rotatable with respect to said stationary magnetic structure; the surface of said stationary magnetic structure opposite the surface having said annular opening therein having radial fins; said radial fins being integral with said stationary magnetic structure and being operative to increase the external area of said stationary magnetic structure and to conduct flux generated by said coil.

4. In an electromagnetic clutch; a stationary magnetic structure and a movable magnetic structure; said stationary magnetic structure having an annular opening therein; said annular opening receiving a coil at the bottom thereof; said movable magnetic structure including a ring shaped member; at least a portion of said ring shaped member being movably positioned within said annular opening of said stationary magnetic structure

and being rotatable with respect to said stationary magnetic structure; said movable magnetic structure being magnetically connected to said stationary magnetic structure by air gaps along the inner and outer diameter of said annular shaped opening in said stationary magnetic structure; said portion of said ring shaped member positioned within said annular opening having a trapezoidal shape whereby the total area of said air gaps on said inner and outer diameters of said annular opening are substantially equal; said coil having a trapezoidal shape cooperating with said trapezoidal shape of said portion of said ring shaped member; the surface of said stationary magnetic structure opposite the surface having said annular opening therein having radial fins; said radial fins being integral with said stationary magnetic structure and being operative to increase the external area of said stationary magnetic structure and to conduct flux generated by said coil.

5. A stationary magnetic structure for an electromagnetic clutch; one external surface of said stationary magnetic structure having radial fin means extending therefrom; said radial fin means being integral with said stationary magnetic structure and being operative to contribute to the cross-sectional flux carrying area of said stationary magnetic structure and to increase the external surface area of said stationary magnetic structure.

6. An electromagnetic clutch; said electromagnetic clutch comprising a driving member and a driven member; said driving member being operatively connected to a first plurality of laminations; said driven member being operatively connected to a second plurality of laminations; the laminations of said first and second plurality of laminations being interleaved; a magnetic structure for generating a magnetic flux through said first and second pluralities of laminations for compressing said laminations; said magnetic structure including a relatively stationary magnetic structure and a relatively movable magnetic structure; one of said driving or driven members being operatively connected to said relatively movable magnetic structure; said stationary magnetic structure having an annular opening therein; said annular opening receiving a coil at the bottom thereof; said movable magnetic structure including a ring shaped member; at least a portion of said ring shaped member being movably positioned within said annular opening of said stationary magnetic structure; said movable magnetic structure being magnetically connected to said stationary magnetic structure by air gaps along the inner and outer diameter of said annular shaped opening in said stationary magnetic structure; said portion of said ring shaped member positioned within said annular opening having a trapezoidal shape whereby the total area of said air gaps on said inner and outer diameters of said annular opening are substantially equal; said coil having a trapezoidal shape cooperating with said trapezoidal shape of said portion of said ring shaped member.

7. An electromagnetic clutch; said electromagnetic clutch comprising a driving member and a driven member; said driving member being operatively connected to a first plurality of laminations; said driven member being operatively connected to a second plurality of laminations; the laminations of said first and second plurality of laminations being interleaved; a magnetic structure for generating a magnetic flux through said first and second pluralities of laminations for compressing said laminations; said magnetic structure including a relatively stationary magnetic structure and a relatively movable magnetic structure; said driving member being operatively connected to said relatively movable magnetic structure; said stationary magnetic structure having an annular opening therein; said annular opening receiving a coil at the bottom thereof; said movable magnetic structure including a ring shaped member; at least a portion of said ring shaped member being movably positioned within said annular opening of said stationary

magnetic structure; said movable magnetic structure being magnetically connected to said stationary magnetic structure by air gaps along the inner and outer diameter of said annular shaped opening in said stationary magnetic structure; the surface of said stationary magnetic structure opposite the surface having said annular opening therein having radial fins; said radial fins being integral with said stationary magnetic structure and being operative to increase the external area of said stationary magnetic structure and to conduct flux generated by said coil.

8. An electromagnetic clutch; said electromagnetic clutch comprising a driving member and a driven member; said driving member being operatively connected to a first plurality of laminations; said driven member being operatively connected to a second plurality of laminations; the laminations of said first and second plurality of laminations being interleaved; a magnetic structure for generating a magnetic flux through said first and second pluralities of laminations for compressing said laminations; said magnetic structure including a relatively stationary magnetic structure and a relatively movable magnetic structure; said driving member being opera-

5
10

tively connected to said relatively movable magnetic structure; one external surface of said stationary magnetic structure having radial fin means extending therefrom; said radial fin means being integral with said stationary magnetic structure and being operative to contribute to the cross-sectional flux carrying area of said stationary magnetic structure and to increase the external surface area of said stationary magnetic structure.
